UNITED STATES PATENT OFFICE.

ALBERT STACY, OF LOTHAIR, KENTUCKY, ASSIGNOR OF ONE-HALF TO MONROE SHEPPARD, OF LOTHAIR, KENTUCKY.

CAR COUPLER.

Application filed July 13, 1922. Serial No. 574,679.

To all whom it may concern:

Be it known that I, ALBERT STACY, a citizen of the United States, residing at Lothair, in the county of Perry and State of Kentucky, have invented certain new and useful Improvements in Car Couplers; and I do declare the following to be a full, clear, and exact description of the invention, such as will enable others skilled in the art to which it appertains to make and use the same.

This invention relates to an improved car coupler and has special reference to a clutch secured to one end portion of a car and adapted to grip a draw-bar which extends from a car to be coupled with the car carrying the clutch.

Another object of the invention is to so construct this clutch that the draw-bar may readily move into engagement with it but cannot be withdrawn until the draw-bar gripping jaws of the clutch are moved to an inoperative position.

Another object of the invention is to provide an improved type of hand-operated jaw releasing mechanism which is provided with an actuating or handle bar extended so that the operator may stand at the side of the car and release the clutch without going between the cars.

Another object of the invention is to provide a housing having an improved interior arrangement including a draw-bar passage, side passages leading from the draw-bar passage to receive the draw-bar engaging jaws, and a rear chamber in which a link forming part of the means for moving the jaws to an inoperative position is positioned.

Another object of the invention is to provide improved means for slidably mounting the two jaws so that they may have movement in opposite directions towards and away from each other.

Another object of the invention is to provide a clutch which will be very compact in its construction and which will only extend downwardly beneath the car body a very short distance.

This invention is illustrated in the accompanying drawings, wherein:

Figure 1 is a view showing the coupler clutch in end elevation.

Figure 2 is a vertical sectional view taken along the line 2-2 of Fig. 1.

Figure 3 is a bottom plan view of the clutch with the bottom plate removed.

Figure 4 is a similar view with a plate removed to show the mounting of the two jaws, the draw-bar being shown locked between the jaws.

Figure 5 is a view similar to Fig. 4 with certain parts shown in section and the draw-bar shown about to be inserted.

Figure 6 is a sectional view taken along the line 6-6 of Fig. 3.

Figures 7 and 8 are sectional views taken along the lines 7-7 and 8-8 respectively of Fig. 4.

This improved coupler clutch is to be secured beneath the car body in position for receiving the draw-bar 1 which extends from another car. This draw-bar is provided with a tapered and enlarged head 2 so that the draw-bar may be easily forced inwardly until the head passes between the jaws of the clutch. After the head has passed the jaws, these jaws will move into engagement with the shaft of the draw-bar and through engagement with the head will prevent withdrawal. The two cars will thus be securely coupled until the jaws are moved to an inoperative position.

This clutch is provided with a housing 3 having side walls 4 and a rear or inner wall 5. Fasteners 6 are passed through this rear wall 5 up into the car body 7 and an additional fastener 8 is passed upwardly through the forward portion of the housing. It will thus be seen that this housing will be firmly secured beneath the body of the car. Blocks 9 are secured in the side portions of the housing in spaced relation thus providing a draw-bar passage 10 between these blocks. This passage 10 communicates at its inner or rear end with a chamber 11 which extends transversely of the housing. These blocks are secured in the housing by the fastener screws 12 and each of the blocks is provided with a pocket 13. These pockets extend from the draw-bar passage 10 and it will thus be seen that the jaws 14 which are slidably mounted in the pockets may be normally held extended across the passage as shown in Fig. 5 but may be moved away from each other to permit insertion of the draw-bar or removal of the same. Ribs 15 extend from the sides of the jaws and are positioned in grooves 16 which extend along the sides of the pockets. Therefore, the two jaws will be permitted of free sliding movement

but will be prevented from dropping out of the pockets. The outer end portions of the jaws are beveled to provide cam faces 17 so that when the tapered head of the draw-bar strikes these cam faces, the jaws 5 will be forced apart. After the head 2 of this draw-bar has passed the jaws, the jaws will be forced into engagement with the shank portion of the draw-bar by means 10 of springs 18 which are positioned in the pockets 13 and have their ends engaged with pins 19 and 20.

A plate 21 is secured to the blocks 9 by fasteners 12 and has its end portions cut to 15 provide space to permit operation of the means for moving the two jaws to an inoperative position. This plate is also provided with slots 23 which receive the hinge brackets 24 carried by the jaws to permit 20 free sliding of the jaws. One side portion of this plate 21 has been further cut to fit about a fulcrum 25 which is secured to one of the side blocks 9. The plate will therefore serve to brace the fulcrum when the 25 means for moving the jaws to an inoperative position is operated.

In order to move the jaws to the inoperative position, there has been provided an operating bar 26 which may be termed a 30 handle bar and is provided at one end with a hand hold 27. This operating bar extends through an opening formed in one of the end walls 4 and at its inner end is provided with a cross head or strip 28 having one 35 end pivotally connected with the hinge bracket of one of the jaws. A lever 29 is pivotally connected with the hinge bracket of the second jaw and, intermediate its length, engages with the fulcrum 25. A link 30 extends longitudinally in the chamber 11 and has one end portion pivotally connected with the lever 29 and its other end portion pivotally connected with the cross head 28. Therefore, when the operating 40 bar 26 is drawn outwardly, one of the jaws will be moved towards an inoperative position by a direct pull and the second will be moved towards an inoperative position and in an opposite direction to the first jaw by 45 means of the link 30 and lever 29. As soon as the handle is released, the springs 18 return the jaws to the operative position. After the blocks 9 have been put in place, a front wall forming strip 31 is put in place 50 and secured to the blocks by fasteners 32. This front wall forming strip is of greater depth than the end walls 4 and rear wall 5 so that it covers the outer edge of the plate 21 and will also cover the outer edge of a cover plate 33 which is put in place and secured to the end walls by fasteners 34. It will thus be seen that when this cover plate 55 33 is secured, it forms a bottom wall for the housing and prevents dust and dirt from 60 entering the housing and interfering with 65

the proper operation of the releasing mechanism and springs. An entrance opening 35 is formed in the front wall forming strip 31 so that the draw-bar 1 may pass into the 70 housing.

When this device is in use, it will be secured beneath the body of the car. The draw-bar will be mounted at the opposite end of the car by any suitable mounting means and will extend to pass through the 75 opening 35 into the draw-bar passage 10. When the two cars are brought together for coupling, the draw-bar passes into the housing and when its head 2 engages the cam faces of the jaws, these jaws are forced apart so that the head may pass beyond them. The springs then move the jaws into engagement with the shank portion of the draw-bar and the jaws will be positioned to engage the head and prevent withdrawal. 80 When it is desired to uncouple the cars, the handle or operating bar 26 is grasped by the handle 27 and drawn outwardly. This causes one of the jaws to be moved into its pocket by a direct pulling action and at the same time, the link 30 is drawn upon to rock the lever 29 against the fulcrum 25 and move the second jaw into its pocket in an opposite direction to the movement of the first jaw. The jaws will thus be drawn inwardly to the inoperative position and the draw-bar can pass outwardly through the passage 10 and opening 35. It will thus be seen that there has been provided a clutch which will operate very efficiently to permit the cars to be coupled automatically and which is so constructed that the cars cannot accidentally become uncoupled. There has further been provided a clutch so constructed that it may be moved to release the draw-bar without it being necessary for the operator to pass between these cars. 95

I claim:

1. In a car coupler, a draw-bar clutch comprising a housing having a draw-bar entrance, blocks in said housing at opposite sides of the entrance to provide a central passage and a transversely extending chamber to the rear of said passage, said blocks having pockets formed therein and communicating with the central passage, jaws slideable in said pockets and extensible across the central passage, springs in said pockets engaging said jaws to yieldably hold the jaws extended for locking engagement with a draw-bar forced between the jaws, a handle bar extending into said housing through one side, a cross head at the inner end of said handle having one end portion extending into said chamber, and its other end extending into one of said pockets and pivotally connected with the jaw therein, a link extending longitudinally in said chamber and having one end pivotally connected with the other end of the cross head of said 100

handle bar, and a lever pivotally mounted and having one end portion extending into said chamber and pivotally connected with the other end of said link, the other end of 5 said lever extending into the other pocket and pivotally connected with the jaw therein.

2. In a car coupler, a draw-bar clutch comprising a housing having a central passage leading from an inlet and communicating with a transversely extending chamber in the rear portion of the housing, the housing being further provided with pockets leading from the entrance passage intermediate the length thereof, jaws slidably 10 mounted in said pockets, hinge brackets carried by said jaws and extending longitudinally thereof beyond the inner ends of the jaws, springs in said pockets engaging the

inner ends of said jaws and yieldably holding the jaws extended in operative position 20 across said inlet passage, a handle bar extending into said housing through one side and having a cross head at its inner end extending transversely of the head and having one end pivotally connected with the hinge 25 bracket of one jaw, a link extending longitudinally in said chamber and pivotally connected with the other end of the head of said handle bar, a fulcrum, and a lever engaging said fulcrum and pivotally connected with said link and the hinge bracket 30 of the other jaw.

In testimony whereof I have hereunto affixed my signature.

ALBERT STACY.
